FRANK L. GEORGE, OF LOS ANGELES, CALIFORNIA.

COMBINATION BALANCE-RAIL PIN AND KEY FOR PIANOS.

1,403,401.

Specification of Letters Patent. Patented Jan. 10, 1922.

Application filed October 11, 1920. Serial No. 416,115.

To all whom it may concern:

Be it known that I, FRANK L. GEORGE, a citizen of the United States, residing at Los Angeles, in the county of Los Angeles 5 and State of California, have invented new and useful Improvements in Combination Balance-Rail Pins and Keys for Pianos, of which the following is a specification.

This invention relates to piano keys and 10 the balance rail pins forming mountings for the keys.

It is the object of the invention to provide a construction whereby piano keys may be readily mounted upon their pins and the 15 keys then accurately leveled and spaced with great ease. It is a further object of the invention to provide for this leveling and spacing of the keys without necessitating the removal of the keys from their pins. It 20 is a still further object of the invention to provide a construction wherein the keys are balanced by placing the fulcrum in the center of the key instead of at the extreme bottom edges of the same and to also provide 25 for strengthening the keys at their balanced points. The improved construction also eliminates to a great extent the friction between keys and their pins and generally effects a saving of labor and material in installing and adjusting piano keys.

In the present construction of piano keys and their balance pins great inconvenience has been experienced due to the wearing down of the felt bushings for the keys. 30 This wearing of the bushings has caused the keys to become unsteady upon their pins and as a result the action of the keys has been uncertain. Furthermore, the present practice of leveling keys by removing the 35 latter from their pins and inserting paper washers until the keys are properly leveled has produced very unsatisfactory results and has also caused a great expenditure of time and labor.

40 In the present construction the keys are properly positioned and the wear is taken up without removing the keys from their pins and by adjusting caps which are threaded on to the balance pins and which 45 form the fulcrum for the keys.

The invention will be readily understood from the following description of the accompanying drawings, in which—

Figure 1 is a fragmentary plan view of 50 a piano key mounted upon a balance rail in accordance with the present invention.

Fig. 2 is a fragmentary side elevation of

a piano key showing the balance rail and a portion of the key in vertical section.

Fig. 3 is a bottom plan view of the piano 60 key taken on the line 3—3 of Fig. 2.

Fig. 4 is an end view of the balance pin employed in the improved construction.

Fig. 5 is a bottom view of the cap for the 65 balance pin.

In the drawings is shown a balance rail 1 which may be of usual construction, and one of the keys mounted upon the same is shown at 2. The key 2 is bored from its under side to form the elongated recess 3, 70 and the forward portion of this recess is provided with a countersunk recess 4 in the base of the same. A bore 5 of reduced diameter extends from this countersunk recess to the upper surface of the key.

75 A key guide 6 extends along the under surface of the key so as to form a cover for the bore 3, and said key guide is mortised into the key at its ends as shown at 7. The key guide may be curved longitudinally 80 upon its under surface as shown at 8 and as is the usual construction. The key guide is provided with an opening 10 extending through the same in alinement with the portion of bore 3 in rear of the countersunk recess 4, and said key guide is also provided with an elongated slot 11 communicating with the opening 10 and extending lengthwise of the key guide in alinement with the countersunk recess 4. The sides of this 85 elongated slot may be provided with usual felt pads 12.

The balance pin upon which the key is mounted is shown in detail in Figs. 2 and 90 4. The pin consists of a shank 14 which 95 is driven into the top of the balance rail in accordance with the usual practice. Above this shank the pin flares outwardly from opposite sides of the shank to form the shank portion 15 of increased width. Above this 100 portion of the pin a threaded shank 16 is provided, which is of approximately the same diameter as the shank end 14. In practice the pin is mounted in the balance rail so that the shank portion 15 is positioned with its 105 increased width extending transversely of the balance rail and in the direction of the length of the key to be mounted upon said pin.

110 A cap 18 is screw seated upon the threaded end 16 of the balance pin, said cap comprising a split sleeve arranged for frictional threaded engagement with the pin, and a head 19 above said sleeve and extending over

the end of the balance pin. The upper surface of this head is transversely slotted as shown at 20 in order that it may be engaged by a screw driver for adjusting the cap upon the balance pin through its threaded connection.

For positioning the key 2 upon its balance pin the cap 18 is inserted through opening 10 into the bore 3, and by then moving the key rearwardly with relation to its balance pin the portion 15 of the pin is received in slot 11 and the cap 18 is moved into alignment with the countersunk recess 4. The key is then lowered upon its balance pin 15 until the head 19 of the cap 18 is seated in the recess 4. The key is now held against lateral displacement by engagement of padded sides of slot 11 against the sides of the portion 15 of the balance pin and at the same time the key is fulcrumed upon the balance pin through engagement of the head 19 of the cap for the balance pin against the base of recess 4. The countersunk recess 4 is positioned approximately midway between the upper and lower surfaces of the key 2 and the fulcrum for the key is thus provided at a point where the movement of the key upon its balance pin will cause the minimum movement between the parts. As a result the frictional wear between the key and its balance pin is reduced materially.

After the keys have been positioned upon their balance pins, in order to level the same, it is only necessary to insert a screw driver through bore 5 so as to engage the grooves 20 of the heads of caps 18, and the caps for the balance pins may then be readily raised and lowered upon the pins until the keys are properly leveled. When the felt pads 12 become worn so that there is a tendency of the keys to move laterally upon their balance pins, the pins are turned in the balance rail until the widened portions 15 of the pins engage the padded sides of slots 11 so as to take up the play between the balance pins and the keys.

Various changes may be made without departing from the spirit of the invention as claimed.

50 What is claimed is:

1. In a piano, the combination with a bal-

ance rail pin, of a key fulcrumed at a point intermediate its top and bottom faces upon said pin, and said key being provided with an opening whereby the balance rail pin 55 may be adjusted without removing the key from said pin.

2. In a piano, the combination with a balance rail pin having a cap adjustable along said pin, of a key fulcrumed at a point intermediate its top and bottom faces upon said cap.

3. In a piano, the combination with a balance rail pin having a cap threaded upon its end for adjustment relative to said pin, 65 of a key fulcrumed at a point intermediate its top and bottom faces upon said cap.

4. In a piano, the combination with a balance rail pin having a cap threaded upon its end for adjustment relative to said pin, of 70 a key fulcrumed at a point intermediate its top and bottom faces upon said cap, said key having a bore extending through the same to its top surface and adapted to receive a tool for engaging said cap to effect 75 adjustment of the latter.

5. In a piano, the combination with a balance rail pin, of a key fulcrumed upon said pin, said pin having a portion of increased transverse width, and said key having an elongated slot through which said pin portion extends, and means adapted to be engaged by a suitable tool for turning said pin to cause engagement of said portion of increased width with the walls of said 85 slot.

6. A piano balance rail pin comprising a shank having lateral projections on its body intermediate its ends, and a cap adjustably positioned on the upper end of said 90 shank.

7. The combination with a piano key provided at a point intermediate its top and bottom surfaces with a bearing and with a slot below said bearing, of a balance rail pin 95 having a portion of increased transverse width arranged on the slotted portion of the key and its upper end seated in the bearing in said key.

In testimony whereof I have signed my 100 name to this specification.

FRANK L. GEORGE.
